METHOD OF PERFORATING GYPSUM LATH

Louis N. Sorensen, Port Clinton, Ohio, assignor to
The Celotex Corporation, Chicago, Ill., a corporation of Delaware

Original application June 8, 1939, Serial No. 278,212. Divided and this application August 27, 1941, Serial No. 408,430

9 Claims. (Cl. 164—125)

1

This invention relates to the method of perforating gypsum lath or the like in the ordinary course of manufacture and article resulting therefrom, so that when the finished lath are delivered from the last or drying operations no further operation is needed before the lath is ready for use.

Heretofore the perforating operation has generally taken place after the lath have come through the dryer and have been bundled prior to shipment; the operation has been done by means of gang drills which leave considerable dust in the packaged lath.

An object of this invention is to provide a perforated gypsum lath which is free from dust; this is highly desirable as the dust falls into the eyes of the mechanic applying the lath; this particularly is true when the lath are being applied to ceiling joists.

Another object of this invention is to provide a means whereby the lath to be perforated is moved forward at intervals or steps to permit the perforating operation while the lath is at rest in the machine during the periods between the forward steps.

Still another object is to provide a means whereby the plugs cut from the lath, may be removed after the perforation is completed.

These and other objects may be seen and noted from the following specifications and its accompanying illustrations, in which:

Fig. 1 is a side elevation of the device and the carrier or conveyor upon which the lath moves.

Fig. 2 is an enlarged top plan view of the perforator partly cut away.

Fig. 3 is an enlarged side elevation of the perforating device, partly in section, the cutting position of the knives being indicated by the dotted lines.

Fig. 4 is a view similar to Fig. 3 but with the knives in the retracted position and the slide in the forward position removing the plugs.

Fig. 5 is an enlarged fragmentary section showing one of the knives as the perforation is completed and the plug thrust within the throat of the knife.

Fig. 6 is a similar view to Fig. 5 but with the knife retracted and the plug about to be pushed from the top of the rod.

Again referring to the drawings a chain 10 is mounted over rolls 11 as illustrated in Fig. 1; adjacent a conveyor of which the driven rolls 12a are a part; the idler rolls 12 serve to support the lath on its journey through the perforator. Cross bars 13 are secured on the chain

2

10 at intervals and lugs 14 are secured on a chain 10a at intervals of one foot or any desired spacing.

A chain 15 drives sprockets 16 and 17 to which are secured pivoting crank arms 18 and 19 respectively, said crank arms being secured eccentrically upon the sprockets 16 and 17 which are secured within a frame 20 on a bearing mount 21.

10 A driven sprocket 22 is secured on a shaft 23 which is driven by means of a chain and clutch (not shown) from the main board machine drive. The chain 15 is mounted on the sprocket 22.

15 A wheel 25 is rigidly secured to the outer end of the shaft 23 and has a short crank arm 26 eccentrically secured to the face thereof on a pivot pin 27, and said arm 26 has a plate 28 secured thereon at its opposite end and a notch 29 therein, thus as the sprocket 22 and wheel 25 revolve with the shaft 23, the short crank arm 26 moves in an eccentric manner against the face of the wheel 25, pivoting on the pin 27, and the free end of the arm on which the notched plate 28 is secured moves back toward the frame 20 until the revolution of the wheel causes said arm to again slide forward whereupon the notch 29 therein engages a lug 14 and moves the chain 10a forward approximately one foot.

20 30 The chain 10a drives a sprocket "A" which in turn drives a chain 10b which engages the sprocket "B" causing the chain 10 to move forward in steps of one foot or any other predetermined distance. Lath are delivered by means of a driven roll 12a to the idler rolls 12 where they are engaged by the bars 13—one of which is at each end of the lath to insure its even travel through the perforator.

25 35 As the rotation of the wheel 25 continues the notched end of the arm 26 moves away from the lug 14 and the motion of the chains 10, 10a, and 10b ceases until the operation is repeated. This causes an intermittent movement of the lath 30 as it travels through the perforating machine; the synchronizing of the retraction of the short crank arm 26 with the upward thrust of the crank wheels 16 and 17 causes the perforation of the lath during that interval when the chain 10 carrying the lath 30 through the perforator, is not moving forward.

30 35 The long crank rods 18 and 19 are pivotally attached at the top thereof to a plate 31 through bearings 32. Rollers 33 mounted on bars 34 move up and down on the frame 20 and keep the perforating machine in a vertical plane.

Rods 35 mounted on the plate 31 through sleeves 36 serve to keep the plate in alignment with a fixed die plate 37 secured to the frame 20 thereabove, the sleeves 39 being secured to the plate 31 by bolts 38.

The rods 35 pass through bearing sleeves 36 secured to the top surface of the fixed die plate 31 by bolts 40, and oil cups 41 lubricate the sliding bearing sleeve 36.

Secured rigidly to the plate 31 through sleeves 42 are circular perforating knives 43, and said knives are fastened to the plate 31 by means of a bolt 71 and lock nuts 72. The bolt 71 passes through the plate 70 to which the knife is welded, and engages in the bottom of the knife plate 31. The circular knives slide up and down on stationary rods 44 secured to a fixed plate 45 secured to the frame 20.

The die plate 37 has apertures 46 therethrough directly above the knives 43 and registering therewith. Plugs 47 extend into the apertures 46 and are held in place by means of a plate 49 to which they are fastened by means of lock nuts 48. Bolts 50 secured through the plate 49 are screwed into the die plate 31 and are retained by lock nuts 75 as shown in Fig. 4 to secure the plugs 47 in a set position within the aperture 46.

The apertures 46 are of such diameter as will allow the circular perforating knives 43 to project therein, whereas the plugs 47 are small enough to fit within the throat of the knives 43.

Thus as the knives 43 pass through the gypsum lath 30, the circular plug or cutting 51 cut therefrom is thrust downward into the throat of the knife 43 by the downwardly projecting end of the plug 47 as the knife enters the aperture 46. This results in a clean uniform cut with the edges of the hole being smoothed by the troweling action of the knives 43 passing through them.

On the downward stroke of the perforating mechanism, the rods 44 thrusting upward through the knives 43 as the said knives move downward, push the circular plugs 51 out of the throat of the knives 43.

As the perforating assembly moves downward an extension arm 52, which is slotted at 53 to encircle a rod 54, strikes a nut 55 secured on the end of said rod, which is a part of a lever operating mechanism.

The rod 54 is movably secured to one end of the balancing lever 56 suspended on a pivot post or bearing 57 mounted on a plate 58 and suspended within the frame 20 and secured thereto by any suitable means.

Movably secured to the opposite end of the balancing lever 56 is a second rod 59, to the lower end of which is secured a weight 60. A pivoting angular lever 61 is secured on a pivot pin 62 mounted through the rod 59 above and adjacent to the weight 60.

The center portion of the pivoting angular lever 61 is pivotally secured on a pin 63 mounted through a bearing bracket 64 secured to the frame 20, the angular leg 61a projecting downwardly within an aperture 65 in a slide 66.

The slide 66 is slidably secured through split guides 67 secured to the die plate 37 and projecting downwardly therefrom, and cross bars 68 are secured between the side bars of the slide 66; thus as the extension arm 52 strikes the nut 55 on the rod 54, the balancing lever 56 dips downward at that end, causing the rod 59 to move upward vertically, this draws the pivoting angular lever 61 upward, the angular leg 61a projecting within the aperture 65 in the slide 66 is thus

thrust forward to a vertical position as shown in Fig. 4 and the slide is thus drawn forward, the cross bars 68 brushing the circular plugs 51 from the rods 44.

When the pressure is released on the nut 55, by the perforating mechanism again moving upward, the weight 60 pulls the rod 59 downward to counterbalance the balancing lever 56 and the slide 66 moves back to its original position with the cross bars out of the path of the knives 43.

Rails 69 secured to the frame 20 by any suitable means such as an angular plate 69a, as shown in Fig. 3, apertures 69b being provided therein to allow the passage of the knives 43 therethrough support the lath 30 in the perforator.

The operation is evident from the above description but may be briefly stated as follows: The laths or pieces of plaster board 30 are advanced step by step through the perforating machine. When the feed is stopped the sliding plate 31, operated by the connecting rods 18 and 19 slides up carrying with it the tubular knives 43 which cut the disks 51 from the lath, as illustrated in Fig. 5, the plugs 47 acting to force the cuttings into the bore of the knives or cutters. When the plate 31 descends the cutters are retracted and the fixed rods 44 eject the pieces 51 from the knives as shown in Fig. 6, and then by the lever mechanism the frame 66 is shifted laterally and its bars 68 dislodge the pieces from the top of the rods 44, as indicated in Fig. 4. The operation is then repeated for the next rows of perforations, and so on indefinitely.

The preferred method which I prefer to use in forming my novel perforated lath wherein the perforations are troweled smooth is to first form the lath on the lath forming machine as at C. The lath after it has been formed is allowed to set as it travels on the conveyor 12a. The conveyor 12a is of such length that the time it takes for the lath to travel from the lath forming machine to the lath perforating machine, the lath has had time to partially set the cementitious material forming the inner lamination of the lath. Where a plurality of rows of lath are simultaneously formed on the lath forming machine, it is permissible to allow some of the lath which are not to be perforated to pass directly into the drier D, while the lath which are to be perforated are shunted to one side of the main conveyor 12a to pass through the lath perforating machine. The shunt conveyor system to the lath perforating machine also permits the lath to set harder so that a better finished perforation is had.

The continuous movement of the lath on the conveyor or shunted conveyor 12a is then transformed to an intermittent motion by the conveyor 10 of the lath perforating machine. The lath or plaster board is advanced step-by-step through the perforating machine. As the lath is advanced, the lath is then perforated during the period when the intermittently actuated conveyor 10 is standing still. After the lath leave the perforating machine, they are transferred from the intermittently actuated conveyor 10 to the continuously moving conveyor 12a. The lath then are conveyed to the drier where they are completely dried. It is obvious from the above disclosed method of forming a perforated lath, that a novel lath has been formed wherein the perforations are troweled smooth; and as the lath is dried, a hard smooth surface is formed within the

perforations without the attendant dust as is the case where the lath are drilled.

It is evident that as the lath is perforated, it is also possible to form means such as partially perforated holes for the reception of nails for starting the nails into the lath or plaster board as it is erected. Referring to Figures 1 to 6 inclusive, novel mechanism has been provided to partially perforate the lath as it travels through the perforator with intermittent motion. There has been provided prick punches 73 in the form of long slender rods pointed on one end and affixed to the plate 31 in a suitable manner such as tapping the plate 31 and threading the ends of the prick punches 73. To lock the prick punches in position, lock-nuts 74 have been provided. The angular plate 69a is provided with apertures 75 to permit the passage of the prick punches 73 as the plate 31 is actuated to perforate the lath as it travels through the perforator with a step-by-step motion. It is, therefore, evident that as the plate 31 is actuated, the prick punches 73 indent the lath 30 at 76 as indicated in Figures 2, 5 and 6. Therefore, as the perforator is actuated, it is obvious that the lath 30 will be partially perforated or indented with a series of indentations along the edge of the lath or throughout the face thereof depending upon the desired pattern of perforations and there has been indicated only a simple pattern of indentations so that the method of indenting and the apparatus may be simply described. It is evident that a more elaborate pattern of perforation may be used without departing from the scope of the invention by providing an increased number of prick punches. Similarly, there may be formed indentations or other forms of perforations which may be formed by this machine wherein the finished lath has suitable indentations or perforations for applying various clips for erecting the lath instead of the usual nailing operation.

In the foregoing specification and in the accompanying claims, the use of the words "set" or "hardened," in referring to the board at or about the time of punching, is to be understood as comprising the use of such words in the sense in which they are commonly used in the art involved. The "set" or "hardening" of the cementitious material at or about the time of punching refers merely to the initial set or hardening of the cementitious material which, with a gypsum core, results from the taking on of additional water by the calcined gypsum, $\text{Ca}_2\text{SO}_4 \cdot \frac{1}{2}\text{H}_2\text{O}$ in converting to $\text{Ca}_2\text{SO}_4 \cdot 2\text{H}_2\text{O}$, a set or hardened condition but with the material still wet. The set or hardened condition referred to is to be distinguished from the finished product which, in its set or hardened condition, and dry, that is with the excess moisture evaporated therefrom, differs in its physical condition in that the initially set or hardened material is relatively soft and somewhat plastic, whereas the finally set, hardened and dry material is brittle, and when cut, broken or crushed tends to break down to a powder or dust.

It will be understood that this invention is susceptible of embodiment in various forms, which are illustrated in the accompanying drawings and that the special details and methods of forming the lath herein set forth may be varied to suit particular purposes without departing from the scope of invention.

This application is a division of application Serial No. 278,212 filed June 8, 1939.

What is claimed is:

1. The method of fabricating a perforated slab of building material comprising a layer of set or hardened cementitious material adhered to surfacing sheets, which comprises the steps: forming the slab, allowing the slab to partially set, positioning a selected portion of the slab over a stationary plug anvil perforating the partially set slab, by a reciprocating annular cutter in cooperation with the plug anvil, and troweling the partially set cementitious peripheral of the perforation causing the periphery of the perforation to be smoothed.
2. The method of perforating a slab of building material comprising a layer of set or hardened cementitious material adhered to surfacing sheets, which comprises as steps: uniformly advancing the slab, changing the uniform motion of the slab to intermittent motion, and between intermittent movements perforating selected portions of the slab after it is intermittently advanced.
3. The method of fabricating a perforated slab of building material comprising a layer of set or hardened cementitious material adhered to surfacing sheets, which comprises the steps: forming the slab, partially drying the slab, advancing the slab by intermittent movement and between the intermittent movements thereof perforating selected portions of the slab, causing the periphery of the perforation of partially dry cementitious material to be troweled smooth, and further drying the slab whereby a perforated slab is had with the periphery of the perforations of the slab clean and smooth.
4. The method of forming indentations for nail markings in a slab of building material comprising a layer of set or hardened cementitious material adhered to surfacing sheets, which comprises the steps: forming the slab, allowing the slab to partially set, and indenting the partially set slab on one face, the other face opposite the indentation firmly supported whereby a pattern of indentations is formed on a surface of the aforesaid slab forming nail markings without deformation of the opposite surface of the slab opposite such indentations.
5. The method of forming indentations for nail markings in a slab of building material comprising a layer of set or hardened cementitious material adhered to surfacing sheets, which comprises the steps: forming the slab, allowing the slab to partially set and indenting the partially set slab by forcing portions of one of the surfacing sheets on one face into the partially set portion of cementitious material the other face opposite the indentation firmly supported whereby as the slab of cementitious material dries, a pattern of nail indentations is formed on one face of the slab without deformation of the opposite surface of the slab opposite such indentations.
6. The method of fabricating a perforated and indented slab of building material comprising a layer of set or hardened cementitious material adhered to surfacing sheets, which comprises the steps: forming the slab, allowing the slab to partially set, positioning the slab with respect to punching and indenting mechanism, the under surface thereof being firmly supported, simultaneously indenting and perforating the partially set slab, and troweling the partially set cementitious peripheral of the perforation causing the periphery of the perforation to be smoothed.

7. The method of perforating and indenting a slab of building material into a pre-arranged pattern of perforations and indentations, which comprises: uniformly conveying the slab to be perforated, changing the motion of the slab from uniform to intermittent, positioning the slab under a punching apparatus, and supported at the point of punching and simultaneously, uniformly and intermittently perforating the slab until the slab is completely perforated and indented into a pre-arranged pattern of perforations and indentations.

8. The method of perforating plaster board comprising the steps; intermittently advancing a sheet of substantially wet plaster board along a support means, reciprocating a gang punch with the punching stroke thereof synchronized with the dwell period of the intermittent advance of the sheet, punching the sheet with the gang punch, receiving in cavities in the punches the 15 plugs cut from the sheet in punching and subsequent to a punching stroke ejecting the cut out punchings from the cavities of the punches.

9. The method for perforating plaster board having a partially set cementitious core with adhered surfacing sheets which comprises the steps of positioning the plaster board on a support, intermittently advancing the plaster board along the said support, simultaneously reciprocating a plurality of annular knives to cut through the plaster board and receive in their open interiors plugs of the plaster board cut therefrom as a consequence of the reciprocation of such annular knives, the cut-out plugs then through continued reciprocatory movement of the annular knives ejected therefrom, the plaster board advanced and the annular knives reciprocated in timed relation whereby the annular knives are reciprocated only during the dwell period of the intermittent advance of the plaster board and the cut out plugs are ejected prior to the completion of the reciprocatory motion of the annular knives and further movement of the plaster board being intermittently advanced.

LOUIS N. SORENSEN.
